THERMOSTAT

Application filed May 12, 1930. Serial No. 451,579.

This invention relates to thermostats and more particularly to those of the open switch type.

Thermostats of the above character generally comprise an elongated tongue actuated by a thermo-sensitive element and cooperating with one or more contacts to form control switches located in one end portion of a single compartment defined by a casing having its walls perforated to permit the free circulation of air about the element. With the contacts thus exposed, dust and other foreign particles carried by the circulating air accumulate on the contact surfaces and prevent proper engagement thereof which causes undue sparking and burning off of the contact points. The sensitivity of the instrument is thereby materially impaired.

20 The primary object of the present invention is to overcome the above objection through the provision of a new and improved casing construction which effectually encloses the thermostat switches without decreasing 25 the required circulation of air around the thermo-sensitive element.

In carrying out this object, the control switches are enclosed effectually through the provision of a partition separating the thermostat casing into a lower compartment through which air may circulate freely and an upper compartment which is completely closed except for a narrow opening in the partition through which the thermostatic 35 tongue projects.

Another object is to secure the partition above mentioned on the removable cover as distinguished from the supporting base of the thermostat, preferably forming the partition integral with the walls of the cover.

40 Other objects and advantages of the invention will become apparent from the following detailed description, in which

Figure 1 of the drawing is a front elevational view partially in section of a thermostat embodying the features of the present invention.

45 Fig. 2 is a right side view of Fig. 1 with the cover shown in substantially central section.

Fig. 3 is a sectional view taken in the plane of line 3—3 of Fig. 1.

Fig. 4 is a perspective view of the interior of the thermostat cover.

While the invention is here described in detail in the preferred form and in connection with a particular type of thermostat, it is to be understood that modifications and alternative constructions made by those skilled in the art to adapt the same to different conditions will lie within the scope of the invention as defined by appended claims.

The thermostat shown by way of illustration in the drawing includes an elongated base 5 adapted to be secured in vertical position against a flat wall surface and supporting at its lower extremity one end of a coiled strip 6 of bimetallic metal which constitutes the thermo-responsive element. Secured to the other end of the strip and projecting upwardly along the center of the base is an elongated flat tongue 7 whose upper end carries a contact which cooperates with two fixed terminals 8 to form control switches which alternately open and close with reversals in the temperature to which the thermal element is exposed. The ends of the terminals 8 are, according to the usual practice, spaced close together and confine the lateral movement of the tongue to a narrow range.

80 The operating parts above described are protected against mechanical injury by a removable cover having a front wall 9 and a peripheral side wall 10, the edge of which fits snugly over the shoulder portion 11 of the base 5 so that the cover is definitely positioned relative to the base. The cover and base thus define an elongated compartment, in the opposite ends of which the switches and the thermal element are disposed. To 85 permit the free circulation of air around the strip 6, the lower portion of the side wall 10 is formed with a series of perforations 12.

90 That portion of the cover enclosing the control switches is unperforated and this end of the compartment is substantially closed through the provision of a partition 13 extending between the two opposite sides of the cover somewhat below the contacts 8 and defining the bottom wall of a separate switch 95 100.

compartment. To form a more rugged construction, the partition is mounted on the cover and to this end the latter is preferably made of molded bakelite so that the partition wall may be readily formed integral with the side and front walls of the cover as is clearly shown in Fig. 4.

At its center the partition is formed with a slot 14 of a width slightly greater than the range of movement of the thermostat tongue. This slot opens at the inner edge of the partition so as to receive the tongue 7 as the cover is fitted onto the base and guided into proper position by the shoulder portion 11. With the cover thus positioned, the inner edge of the partition abuts against the face of the base as shown in Fig. 3.

With this simple construction, the control switches are housed in a substantially closed compartment from which dust and foreign particles are effectually excluded by reason of the fact that the only opening into the switch compartment is through the lower defining wall thereof, which opening may be made small because of the relatively narrow range of motion of the thermostat tongue which projects into the switch compartment. Casting the partition integral with the cover affords an inexpensive method of forming the partition and avoids the danger of dislocating the partition and thereby impairing the thermostat in the act of placing the cover onto the base. Inasmuch as the partition is carried by the cover, it is removed with the cover and therefore does not interfere with the adjustment of the thermostat or cleaning of its contacts.

I claim as my invention:

1. A thermostat comprising, in combination, an elongated substantially flat base, a removable cover composed of molded insulating material and having a substantially flat front wall and a peripheral side wall, said cover being adapted to fit onto said base and cooperating therewith to form an elongated compartment, a coiled bimetallic strip supported on said base at one end of said compartment, an elongated substantially flat tongue supported by said strip and projecting longitudinally of said compartment, a contact mounted on said base at the end thereof opposite said strip and cooperating with the free end of said tongue to form a control switch, and a partition molded integral with the cover walls and extending transversely across the cover to divide said compartment into a perforated portion containing said thermostatic strip and an unperforated portion substantially closed by said partition and containing said switch, said partition having a slot therein open at its inner edge so as to receive said tongue when said cover is fitted onto said base.

2. A thermostat comprising, in combination, an elongated base, a thermo-sensitive

element mounted on one end of said base, a circuit terminal mounted at the other end of said base, an elongated tongue extending longitudinally of the base and having one end associated with said element and the other end cooperating with said terminal to form a switch, a casing enclosing the device and having the portion thereof adjacent said bimetallic element perforated to permit free circulation of air therethrough, the remainder having solid walls, and a partition cast integrally with said casing dividing said perforated from said unperforated portions to form a substantially dust-proof compartment for said switch, said partition having a narrow slot receiving said tongue when said casing is placed on said base.

3. A thermostat comprising, in combination, an elongated base, a cover adapted to fit on and cooperating with said base to form an elongated compartment, a partition formed integral with said cover and dividing said compartment into a substantially closed portion at one end, the walls defining the compartment being perforated to permit the circulation of air through the other end portion of the compartment, a thermo-sensitive element mounted on said base in said open end portion, an elongated member arranged to be actuated by said element and extending longitudinally of said compartment through said partition into said closed portion, and a contact within the closed portion of said compartment cooperating with said tongue to form a control switch.

4. A thermostat comprising, in combination, an elongated base adapted to be mounted in an upright position, a bimetallic strip responsive to temperature variation and mounted at the lower end of said base, a circuit terminal mounted at the upper end of said base, an elongated tongue extending longitudinally of the base and having one end rigid with said bimetallic strip and the other end cooperating with said terminal to form a switch, a casing forming a cover for the device, the lower portion of said casing enclosing the bimetallic element having perforations to permit free circulation of air therethrough, the remaining lower portion being unperforated, and a partition within said casing dividing said perforated from said unperforated portion to form a substantially closed chamber for said switch, said partition having a narrow slot through which said tongue projects.

5. A thermostat comprising, in combination, a casing defining an elongated compartment, a partition extending transversely of said compartment and dividing the same into a substantially closed portion at one end, said casing having at its other end portion a perforated wall permitting the circulation of air therethrough, an elongated switch actuating member projecting longi-

tudinally of said compartment through an opening in said partition, a thermo-sensitive element mounted in the open end portion of said compartment and arranged to actuate said member, and a contact mounted in the closed end portion of said compartment and cooperating with said member to form a control switch.

6. An automatic control device for air 10 conditioning systems comprising, in combination, an elongated casing having perforated walls at one end thereof so as to permit the free circulation of air therethrough, a partition extending across said casing near 15 the other end thereof and cooperating with such end to form a substantially closed compartment, a contact switch disposed in said closed compartment, an element responsive to changes in the condition of the circulating 20 air and mounted in the end of said casing opposite said compartment, and an elongated member extending longitudinally of the casing through said partition having one end associated with said element and the 25 other end arranged to actuate said switch in response to said element.

7. A thermostat comprising, in combination, a casing comprising two separable parts adapted when assembled to define a chamber 30 having one section defined by closed walls and another section defined by walls perforated to permit air circulation therethrough, thermostatic means in said last mentioned section including an elongated member laterally movable as an incident to temperature changes, a contact in said closed section cooperating with said member to form a control switch, said contact and thermostatic means being mounted on the same one of 35 said parts to permit adjustment of the thermostat prior to assembly of the parts, and a partition between the sections of said chamber having an aperture therein adapted to receive said member as an incident to assembly of said parts and of a size permitting of the necessary lateral movement of 40 said member.

In testimony whereof, I have hereunto affixed my signature.

50 HOWARD D. COLMAN.
